United States Patent Office

Des. 211,317
Patented June 11, 1968

211,317

DECANTER

Budd S. Sheesley, New York, N.Y., assignor to Schenley
Industries, Incorporated, New York, N.Y., a corporation of Delaware

Filed Feb. 16, 1967, Ser. No. 5,837

Term of patent 14 years

(Cl. D9—32)

FIG. 3

FIG. 2

FIG. 1

FIG. 4

FIG. 5

FIGURE 1 is a front elevational view of a decanter embodying my new design;

I claim:

The ornamental design for a decanter, as shown.
